UNITED STATES PATENT OFFICE.

CHARLES OSCAR ANDERSON, OF OMAHA, NEBRASKA, ASSIGNOR TO ANDERSON BRAKE ADJUSTER COMPANY, OF OMAHA, NEBRASKA, A CORPORATION OF NEBRASKA.

AUTOMATIC SLACK ADJUSTER.

Application filed September 17, 1923. Serial No. 663,185.

To all whom it may concern:

Be it known that I, CHARLES OSCAR ANDERSON, a citizen of the United States, residing at Omaha, in the county of Douglas 5 and State of Nebraska, have invented certain new and useful Improvements in Automatic Slack Adjusters, of which the following is a specification.

My invention relates to railway brake apparatus, and particularly to automatically operated adjusting devices for maintaining a constant clearance between the wheels and brake-shoes when the brakes are in release position, whereby to constantly compensate 10 the wear of the brake-shoes, so that applying of the brakes is effected by uniform travel of the brake-actuating means. It is the object of my invention to provide a simple and efficient brake-adjusting device 15 of this character, especially adaptable for use in cases where there is a brake-beam and equalizer-beam consisting of flat bars disposed adjacent to each other in a common plane.

20 In the accompanying drawings Fig. 1 is a plan view of a truck-frame and brake-rigging having my automatic adjuster applied thereto, Fig. 2 is a detail plan view of the adjuster, and Fig. 3 is a side view 25 of the same, a portion being in longitudinal section.

In the truck-frame represented in Fig. 1 the longitudinal side-members 10 have the usual cross-bracing 11 and journal-boxes 12, 30 the axles 13 and wheels 14 being represented in dotted outline only. At each end of the frame are the transversely extending brake-beams 15 of which the ends are adjacent to the wheels 14 and have the usual brake-heads 16 to which are secured the renewable brake-shoes 17. The brake-beams are swingably supported by pivoted hangers 18 depending from the hanger-rods 19 which extend transversely between the side frame-members 10 35 above the brake-beams. Each brake-beam is formed by a flat bar disposed horizontally edgewise, and the equalizer-beams 20 are formed by similar bars of less length, disposed parallel with the brake-beams and adjacent to the edges thereof opposite the wheels. The ends of the equalizer-beams are connected with each other by longitudinal rods 21, whereby any movement of one beam is communicated to the other. 40 Near the center of each equalizer-beam is

secured a strut 22 which extends outwardly, or longitudinally of the truck away from the respective brake-beam. Upon said struts 22 are fulcrumed the brake-levers 23 which extend therefrom laterally, and to the longer arms of the brake-levers are connected the 45 brake-rods 24, by means of which the brakes are applied. In the usual construction of this type of brake-rigging, the short arm of each brake-lever is connected with the respective brake-beam by a yoke or clevis 25 which straddles the equalizer-beam and is connected with the brake-beam near the center thereof, wear of the brake-shoes being compensated by means of turnbuckles 26 50 which vary the effective length of the rods 21 connecting the ends of the equalizer-beams. In equipping the brake-rigging with my automatic adjuster, the latter replaces the clevis connection between the 55 brake-lever and brake-beam at one end of the truck, while at the other end the usual connection is left undisturbed, as shown at the left of Fig. 1.

The automatic adjusting device has a 60 clevis consisting of a pair of symmetrical arms 27 which straddle the beams 15 and 20, and at their forward ends are connected with the short arm of the brake-lever 23 by means of the pivot-bolt 28. Rearwardly of 65 the brake-beam the end-portions of the clevis-arms 27 form the upper and lower halves of a split cylindrical head 29, of which the terminal portion is threaded to receive the collar 30 by which the two parts 70 of the head are secured together. Within the head 29 is revolvably fitted the spool-shaped body 31 of the adjusting-sleeve, which is threaded internally to receive the 75 adjusting-screw 32. The latter extends forwardly from the sleeve between the clevis-arms 27 and has a forked head 33 which straddles the brake-beam and to which it is pivotally connected by the bolt 34. Said bolt also extends through the longitudinal 80 slots 35 in the clevis-arms, the bolt fitting slidably in said slots and constituting a 85 guide for holding the clevis and adjusting-screw in longitudinal alinement. At the end of the adjusting-sleeve body 31 there is a 90 tubular extended portion 36 of which the bore is of slightly greater diameter than the screw, whereby the screw may freely enter 95 said tubular portion. At the rear end of the portion 36 is the hollow hexagonal extension 100 105 110

37, to which a wrench is applied when resetting the adjuster for the insertion of new brake-shoes. The clutch-sleeve 38 is disposed about the extended portion 36 of the 5 adjusting-sleeve, the latter having a conical clutch-surface 39 with which the conically-bored end-portion of the sleeve 38 is frictionally engaged. The rear end of the clutch-sleeve is engaged at diametrically opposite points by the ends of a shouldered cross-pin 40 which extends through a slot in the adjusting-sleeve at the juncture of the portions 36 and 37. The intermediate portion of said cross-pin 40 passes through the 10 head of a plunger 41, which has a stem extending through the end of the part 37. A coil spring 42 is disposed about the plunger-stem between the head thereof and the end of the part 37. The pressure of said spring 15 is communicated by the cross-pin to the end of the clutch-sleeve and tends to move said sleeve longitudinally of the part 36, to thereby hold the clutch-sleeve in yielding engagement with the conical clutch-surface 39 of the 20 adjusting-sleeve. For convenience in assembling and disconnecting the parts, a portion of the plunger-stem which protrudes from the part 37 has a transverse slot 43 through which a wedge may be inserted to 25 move the plunger rearwardly and disengage the cross-pin from the end of the clutch-sleeve. When the plunger has been moved back far enough to withdraw the shoulders of the cross-pin from within the end of the 30 clutch-sleeve, the cross-pin may be removed, after which the clutch-sleeve may be withdrawn off the end of the adjusting-sleeve. Normally, the spring pressure upon the plunger retains the cross-pin in the position 35 at which its shoulders enter the end of the clutch-sleeve, and the pin is thereby prevented from accidental dislodgment. A removable screw-plug 44 is provided at the upper side of the clutch-sleeve, for convenience in introducing a lubricant into the 40 space between said sleeve and the adjusting-sleeve. In the side of the inner sleeve-portion 36 there is an oil-hole 45 through which the lubricant may enter and thus reach the threads of the adjusting-screw. At the 45 upper side, near the front end of the clutch-sleeve, there is a U-shaped vertically extending flange 46 adapted to receive the sphero-segmental head at the end of one arm of the bell-crank 47, the latter being mounted pivotally upon a stud 48 secured to the upper side of the clevis-head 29. The other arm of the bell-crank extends laterally of the clevis, and to the end thereof is pivotally connected the rear head 49 of a rod 50 which extends forward parallel with the clevis-arms. At its front end the rod 50 is threaded and is screwed into a slotted head 51, a locknut 52 being provided on the rod 55 adjoining the head. The end of the rod is

extended into the rear portion of the slot in the head and forms an abutment or stop for limiting in one direction the relative motion of the head and the pin 53 which extends through the slot. Said pin 53 is an upward extension of the fulcrum-pin which connects the brake-lever with the strut 22 of the equalizer-beam. A washer and cotter-pin at the upper end of the pin 53, as shown, serve to hold the head 51 in place thereon. 70

Any suitable release-springs may be provided in connection with the brake-beams for moving the brake-shoes out of contact with the wheels except when the beams are moved to braking position by tension upon one of the rods 24. The release-springs are not shown in the drawing, but it will be understood that any ordinary arrangement thereof may be employed. Applying of the 80 brakes, or movement of the brake-beams to engage the brake-shoes with the wheels, is caused by movement of either brake-rod 24 while the other is held stationary. During the applying movement, the brake-beam and equalizer-beam at each end of the truck move apart, or relatively away from each other, their approximate relation at release and applied positions being indicated, respectively, by the full-line and dotted-line 85 representations of the beams in Fig. 2. In said figure is also shown in full and dotted lines, respectively, the release and applied positions of the brake-lever, corresponding with a normal brake-shoe clearance at release position. It will be seen that during the brake-applying and releasing movements the fulcrum-pin 53 will move longitudinally of the slot in the head 51 of the rod 50, since the fulcrum-pin moves with the equalizer-beam, while the rod 50 tends to move with the clevis and brake-beam. The length of the slot in the head 51, from the front end to the adjustable abutment formed by the end of the rod, is made such that during a normal travel of the parts the fulcrum-pin will merely move from end to end of the slot, while a movement in excess of the established minimum or normal motion will cause the rod 50 to be moved longitudinally an amount corresponding to the 90 excess travel of the fulcrum-pin. Thus, whenever there is an excessive travel of the parts in applying and releasing the brakes, such excess movement will result in a longitudinal reciprocation of the rod 50, its forward motion occurring at the end of the applying movement, and its rearward motion being at the end of the releasing movement. The longitudinal reciprocating motion of the rod 50 causes an oscillation of the lever or bell-crank 47 about the stud 48, and the motion of the rear arm of the bell-crank causes a slight rotation of the clutch-sleeve about its axis in alternating directions, the sphero-segmental form of the head at the 95 100 105 110 115 120 125 130

- end of the bell-crank allowing the rocking motion of the sleeve, relative to the arm, to take place without causing binding between said head and the U-flange 46. By reason 5 of the frictional engagement of the clutch-sleeve with the clutch-surface 39 of the adjusting-sleeve, the latter tends to move with the clutch-sleeve, and such movement of the adjusting-sleeve will occur if the friction at 10 the clutch-surface is greater than the retarding-friction upon the adjusting-sleeve, said retarding-friction being the sum of the friction between the sleeve and screw 32 and between the sleeve and the clevis-head 29. 15 If the retarding-friction is greater than the clutch-friction, then the clutch will slip and no movement of the adjusting-sleeve will be caused. The parts are so proportioned that the last-named condition will prevail during 20 the movement of the clutch-sleeve caused by applying the brakes, the retarding-friction being greater at this time because of the pressure of the clevis-head against the adjusting-sleeve, and the pressure of the latter 25 against the threads of the screw 32. At the end of the releasing movement, however, the retarding-friction is greatly reduced, and becomes less than the clutch-friction, so that the movement of the clutch-sleeve results 30 in turning of the adjusting-sleeve. The direction of this movement is such that the screw 32 is moved rearwardly or into the sleeve, and the brake-beam is thereby moved closer to the rear end or head 29 of the clevis. The clearance between the brake-shoes and wheels is thus reduced, so that less movement of the brake-lever is required at 35 the next application of the brakes. If, however, the brake-shoe clearance is still too great, so that excess movement of the parts is required to apply the brakes, the clutch-sleeve will be again actuated, and a further adjustment automatically effected upon the releasing of the brakes; the adjusting action 40 being continued at each application and release of the brakes until the clearance is reduced to the desired normal. As hereinbefore mentioned, when the brake-shoes have been worn out and before new brake-shoes are inserted, the automatic adjusting mechanism is re-set by applying a wrench to the hexagonal end 37 of the adjusting-sleeve, and said sleeve turned in the direction opposite to that in which it is moved by the clutch, until the clearance between the brake-heads and wheels is sufficient to receive the new shoes. 45 Now, having described my invention, what I claim and desire to secure by Letters Patent is: 50 1. In a railway brake mechanism, the combination with a brake-beam and an equalizer-beam arranged adjacent to and substantially parallel with each other and movable from and toward each other to apply 55 and release the brakes, a brake-lever fulcrumed on the equalizer-beam, and an actuating member connected with the brake-lever, of a clevis comprising a head and spaced arms straddling the brake-beam and equalizer-beam and pivotally connected with the brake-lever, a rotatable adjusting-sleeve held in fixed longitudinal relation to said clevis-head, an adjusting-screw having one end connected with the brake-beam and a threaded portion engaging the adjusting-sleeve, a clutch-sleeve mounted on said adjusting-sleeve and held in frictional engagement therewith, and means actuated during excess travel of the brake-lever for rotating said clutch-sleeve in alternating directions at the ends of the brake-applying and brake-releasing movements. 60 2. Automatic slack-adjusting means for brake-mechanism having a brake-beam and equalizer-beam adjacent to and relatively movable from and toward each other to apply and release the brakes, comprising a brake-lever fulcrumed upon the equalizer-beam, a screw-threaded member connected with the brake-beam and extending therefrom at the side opposite the equalizer-beam, a threaded adjusting-sleeve engaging said screw-threaded member, a clevis having a head in which said adjusting-sleeve is held 65 revolvably, said clevis having arms straddling the brake-beam and equalizer-beam and pivotally connected with the brake-lever, a clutch-sleeve mounted coaxially with the adjusting-sleeve and frictionally engaged therewith, a lever fulcrumed on the clevis-head and having an arm connected with the clutch-sleeve, and a rod pivotally connected at one end with said lever and at the other end connected loosely with the 70 brake-lever fulcrum-pin, whereby said rod and lever are actuated to rotate the clutch-sleeve during the brake-applying and releasing movements when the relative motion of the brake-beam and equalizer-beam is greater than normal. 75 3. A structure as set forth in claim 1, in which the clevis-head is divided in an axial plane, each portion of the head being integral with one of the arms, the adjusting-sleeve having a spool-like portion of which the central part is embraced by the head and the end-flanges abut the ends of the head to prevent relative axial movement of the sleeve and head, and an integral annular collar surrounding the head to hold its parts together. 80 4. A structure as set forth in claim 2, in which the loose connection between the rod and brake-lever fulcrum-pin comprises a head having a longitudinal slot through which the fulcrum-pin extends, the end of the rod being threaded and said head screwed thereon, the end of the rod extending into a part of the slot in the head and 85 120 125 130

forming an adjustable abutment for limiting movement of the fulcrum-pin in said slot.

5. A structure as set forth in claim 2, in which the frictional engagement between the clutch-sleeve and adjusting-sleeve is effected by means of a spring inclosed in a portion of the adjusting-sleeve which protrudes from the end of the clutch-sleeve, 10 a plunger engaged by the spring and having a stem extending through the end of the adjusting-sleeve, and a cross-pin extending transversely through said plunger and through longitudinal slots in the adjusting-sleeve, the ends of said pin being shoul-

dered and engaging the end of the clutch-sleeve.

6. A structure as set forth in claim 1, in which the adjusting-screw has a forked head fitting about the brake-beam and between the clevis-arms, said arms being longitudinally slotted, and a bolt extending through the brake-beam and forked head to pivotally connect the same, said bolt extending also through the slots of the clevis-arms and fitting slidably therein as a guide for holding the clevis and adjusting-screw in longitudinal alinement. 20 25

CHARLES O. ANDERSON.
